UNITED STATES PATENT OFFICE.

WILLIAM F. PERKINS, OF CHICAGO, ILLINOIS, ASSIGNOR TO THE WEBSTER M'F'G COMPANY, OF TIFFIN, OHIO.

CONVEYER.

1,279,579.

Specification of Letters Patent. Patented Sept. 24, 1918.

Application filed March 23, 1918. Serial No. 224,243.

To all whom it may concern:

Be it known that I, WILLIAM F. PERKINS, a citizen of the United States, residing at Irving Park Station, Chicago, in the county 5 of Cook and State of Illinois, have invented certain new and useful Improvements in Conveyers, of which the following is a specification.

This invention relates to conveyers and 10 more particularly to the driving mechanism for endless bucket conveyers used in handling caustic for example.

One of the objects of the present invention is to provide a simple and practical improved driving mechanism for conveyers of the above general type which may be inexpensively manufactured and installed. A further object is to provide a mechanism of the above general character in which the pulsating movement heretofore incident to conveyer mechanisms of this general character is eliminated, thereby preventing agitation or spilling of the contents of the buckets. A further object is to provide 25 mechanism of the above general character which will be reliable and efficient in use and operation.

Other objects will be in part obvious from the annexed drawings and in part indicated 30 in connection therewith by the following analysis of this invention.

This invention accordingly consists in the features of construction, combination of parts and in the unique relations of the 35 members and in the relative proportioning and disposition thereof, all as more completely outlined herein.

To enable others skilled in the art so fully to comprehend the underlying features thereof 40 of that they may embody the same by the numerous modifications in structure and relation contemplated by this invention, drawings depicting a preferred form have been annexed as a part of this disclosure, and in 45 such drawings like characters of reference denote corresponding parts throughout all the views, in which—

Figure 1 is an elevational view partly in section showing a portion of the conveyer system with the driving mechanism applied thereto;

Fig. 2 is a detail transverse sectional view;

Fig. 3 is a detail perspective view of a driving element.

In order that a clearer perception of the

present invention may be had, it may be stated that in what may be termed "chain drive mechanism" for endless conveyers heretofore used, there has been the objection of a certain amount of shock at the 60 moment of contact between the driving and driven members which produces a pulsating movement in the bucket chain. Such agitation however slight is particularly undesirable where the buckets contain liquids 65 such as caustic, having crystallizing action, as they cool or evaporate. The present invention is directed to the application of a chain drive for an endless bucket conveyer so constructed, positioned and arranged with 70 respect to the driven elements that this pulsating movement will be to a large extent, if not entirely, eliminated.

These objects, among others, are accomplished in the embodiment of the invention 75 hereinafter described by constructing the driving mechanism in the form of a substantially elliptical endless chain positioned within the circuit formed by the endless bucket conveyer whereby the driving instrumentalities proper are gradually brought into engagement with the driven instrumentalities until they exert their maximum pressure and then gradually moved out of contact therewith, thus eliminating as much as 80 possible the shock heretofore incident to this broad type of conveyer mechanism.

As herein shown and described the conveyer comprises a plurality of buckets 6 connected along their side edges by links 7 90 which are in turn pivotally connected with adjacent elements at 8. Suitable rollers 10 are provided at each pivot point 8 adapted to travel along track 11. This bucket circuit may be of any desired type having 95 filling and dumping stations according to the use to which it is to be put.

At any convenient point within the circuit is positioned the driving mechanism which comprises a pair of sprocket wheels 12 and 13, one of which (12) is adapted to be driven from any suitable source of power through a system of reducing gearing 14 in order to drive an endless chain 15 of any desired type. This chain, however, is preferably of 100 the duplex type and comprises a series of links 16 pivotally connected to each other at 17 and provided with rollers 18 adapted to travel along a track 20 at the upper part and hang free at the lower part. 110

Pivoted hooks 21 (Fig. 3) having curved faces 22 and being provided with rearward overbalancing extensions are associated with certain pivots and are so positioned with respect to the transverse dimension of the conveyor as to engage the rollers 10 of the bucket conveyor (Fig. 2) and thus drive the same in a general clockwise direction. It is to be seen by reference to Fig. 1 that the driving chain 15 occupies a substantially elliptical position with a portion of the longer arc substantially tangential to the line of pull of the main conveyor. This driving chain is a short pitch chain, the unit of which is less than any multiple by which the pitch of the main carrier is divisible; the idea being that the variation in the chain that is not a multiple pitch of the main chain would cause the pulling hook on the drive chain to contact with the rollers on the main chain at intervals, such that there would be one and only one pulling hook in full contact at one time on each side of the carrier, and this would contact the main rollers in a manner such that the slight variation in the pitch of the driving chain would in no manner tend to cause the main carrier chain to pulsate.

Thus the hooks 21 gradually come up into engagement with the rollers 10 and as they move relatively toward the right exert by reason of their curved engaging surfaces 22 a gradually increasing pressure upon the roller for a relatively short period of time or until the next succeeding hook has come into full engaging position at which time the first hook gradually moves out of full pressure contact and finally entirely leaves its engagement with the roller 10. In other words the hooks approach up underneath main carrier rollers in such a manner that the fore part of the hook supports the roller then as the chain travels ahead the hook is thrown up in a horizontal position and gradually takes the load off the hook ahead.

From this description it will be seen that the driving instrumentalities represented by the hooks 21 gradually move into contact with the driven instrumentalities or rollers 20 with a gradually increasing pressure and then move out of engagement therewith while the next pair of driving and driven instrumentalities are coming into full operation, thereby eliminating the shock incident to other types of driving mechanism, and in which certain shock or impact occurs to produce a pulsating movement which is desired to be overcome by the invention herein disclosed. For instance, an ordinary sprocket when working with a long pitch chain such as is used with this particular machine, causes the chain to vary in its speed, that is, when the chain is on the sprocket the radius around which the speed of the chain travels would be the distance

from the chord or pitch length of the chain to the center of the wheel, and when the chain is coming on the sprocket then the radius is from the center of the wheel to the center of the chain articulation point or joint, making the difference in the radius of the actions between $\frac{3}{4}$ and $1\frac{1}{2}$ ", which on slow speed such as is used in this particular case, gives a very marked pulsation motion to the chain which is very objectionable as before mentioned.

It will be observed that, in the position where the hook is exerting its maximum driving effect, as well as in the positions on each side thereof, the curved face of the hook engages its individual conveyor member on both sides of the line drawn from the pivot of the hook through the center of the conveyor member. For this reason, when the hooks are brought into their engaging position, all of the thrust of the conveyor chains is transmitted through the pivots of the hooks. This obviates the necessity of providing separate guides for the overbalanced ends of the hooks and eliminates the friction which would result were such guides used.

It is thought from the above description that the operation and method of use of an apparatus of this character will be clear to those familiar with the art and a further detailed statement thereof is unnecessary.

I realize that considerable variation is possible in the details of construction and arrangement of parts without departing from the spirit of my invention, and I therefore do not intend to limit myself to the specific form shown and described.

Having thus described my invention what I claim as new and desire to secure by Letters Patent is:

1. In an apparatus of the character described, a conveyor having spaced members, an endless driving element having pivoted overbalanced driving instrumentalities thereon spaced apart a distance less than the spacing of said members and arranged to engage said spaced members at points on both sides of a line between the center of said spaced members and the pivots of said driving instrumentalities to cause the entire thrust of each of said driving instrumentalities being transmitted through the pivots, and means for guiding one flight of the driving element gradually toward the conveyor to carry the driving instrumentalities thereon with successive engagement with the spaced members, and then away from the path of movement of the conveyor.

2. An apparatus of the character described including a conveyor comprising links and spaced transversely extending members, an endless driving element coacting therewith and comprising links, and spaced driving instrumentalities pivotally

- mounted on the driving element, and having upwardly and rearwardly curved formed faces and rearward overbalancing extensions, the pivotal axis of each instrumentality being approximately in line with the curved face thereof, and the distance between said instrumentalities being less than the distance between said members on the conveyer, and means for guiding a flight of the driving element gradually toward the conveyer, then approximately parallel thereto, and then away from the conveyer.
3. An apparatus of the character described including a conveyer comprising links and spaced transverse rods carrying supporting rollers, endless driving elements moving in the same direction as the conveyer, one on each side thereof, and each element comprising links, certain of the links at spaced intervals having ears, driving members pivoted to the ears, intermediate its ends, the forward end of each member being upwardly and rearwardly curved to fit beneath and behind a corresponding roller on the conveyer, each member having a rearward extension, with a downwardly projecting lug, the distance between the curved faces of the members being less than the distance between the said rollers, and tracks over which the upper flight of the endless element passes, guiding the element gradually toward and in the direction of said conveyer, then parallel thereto, and then away therefrom.
4. In an apparatus of the character described, a conveyer having spaced members, an endless driving element, a plurality of overbalanced driving members mounted on said endless driving element, each of said driving members having a curved face arranged to engage the spaced members of the conveyer on each side of a line between the pivot and the center of the engaged members, and means for guiding said pivoted drive members successively into position for exerting a maximum driving force on said conveyer members.
5. In an apparatus of the character described, a conveyer having spaced members, an endless driving element, a plurality of overbalanced driving members mounted on said endless driving element, each of said driving members having a curved face arranged to engage the spaced members of the conveyer on each side of a line between the pivot and the center of the engaged member, and means for guiding said pivoted drive members successively into position for exerting a maximum driving force on said conveyer members, the driving member in the

rear of the one in driving position being arranged to exert a lifting force on the conveyer member.

6. In an apparatus of the character described, a conveyer having spaced members, an endless driving element, a plurality of overbalanced driving members mounted on said endless driving element, each of said driving members having a curved face arranged to engage the spaced members of the conveyer on each side of a line between the pivot and the center of the engaged member, and means for guiding said pivoted drive members successively into position for exerting a maximum driving force on said conveyer members, the driving member in the rear of the one in driving position being arranged to exert a lifting force on the conveyer member, and the driving member in advance being partly disengaged from its respective conveyer member.

7. In an apparatus of the character described, a conveyer having spaced members, an endless driving element, a plurality of overbalanced pivoted driving members mounted on said endless driving element, each of said driving members being arranged to engage one of said spaced members at points on both sides of a line between the center of the spaced members and the pivot of said driving member to transmit all of the driving thrust through its pivot.

8. In an apparatus of the character described, a conveyer having spaced members, an endless driving chain, a plurality of pivoted hooks carried by said chain, each of said hooks having a curved face arranged to engage one of said spaced members at points on both sides of a line between the center of the member and the pivot of the hook.

9. In an apparatus of the character described, a conveyer having spaced members, an endless driving chain, a plurality of pivoted hooks carried by said chain, each of said hooks having a curved face arranged to engage one of said spaced members at points on both sides of a line between the center of the member and the pivot of the hook, said endless chain having a portion parallel with the direction of movement of the conveyer, and the engagement of the hooks taking place during their travel along said parallel portions.

In testimony whereof I affix my signature in presence of two witnesses.
